Patented Jan. 29, 1918.

By *Geo. P. Kimmel*
Attorney

UNITED STATES PATENT OFFICE.

REID J. McCREDIE, OF BUFFALO, NEW YORK.

SHOE-POLISHING CABINET.

1,254,821.

Specification of Letters Patent. Patented Jan. 29, 1918.

Application filed March 19, 1917. Serial No. 155,843.

To all whom it may concern:

Be it known that I, REID J. McCREDIE, a citizen of the United States, and resident of Buffalo, in the county of Erie and State 5 of New York, have invented certain new and useful Improvements in Shoe-Polishing Cabinets, of which the following is a specification.

The present invention relates to new and 10 useful improvements in a shoe polishing cabinet and has particular reference to a casing that is of such a configuration as to receive the necessary outfit for polishing shoes compactly and that is of a slightly appearance thus rendering the device particularly attractive to persons traveling.

A still further object of my invention is to provide a device of the character mentioned that is comparatively simple and durable in 20 construction, and that may be manufactured and placed on the market at a minimum cost.

Another object of the invention is to provide the upper portion of the casing of a configuration corresponding to that of the 25 bottom of a shoe so that the same may be retained in the desired position while polishing.

Other improvements and novel details in the construction and arrangement of the 30 various parts of the shoe polishing cabinet will be brought out more in detail in the description to follow, which, for a clear understanding of the invention, should be considered in connection with the accompanying 35 drawings, forming a part hereof, and wherein is disclosed, for the purpose of illustration, convenient and satisfactory embodiments of the invention. It is to be noted, in this connection, that minor changes in the 40 construction and arrangement of the parts may be made without departing from the spirit of the invention or the principle of operation of the various parts.

Reference is to be had to the accompanying 45 drawing, forming a part of this specification, in which similar reference characters indicate corresponding parts throughout the several views.

In the drawing:

50 Figure 1 is a perspective view of my improved shoe polishing cabinet in closed position;

Fig. 2 is a longitudinal sectional view of the same, and

55 Fig. 3 is a detailed view showing the

means of retaining the brush in engagement with the casing.

In its general organization the shoe polishing cabinet comprises a substantially oblong cabinet designated C in its entirety. 60 The end 5 of the cabinet is of a substantially annular configuration to receive the standard forms of shoe polishing cans 6 and as particularly set forth in Fig. 2. The opposite end of the top 7 of the casing is depressed at 8 to provide means to receive the heel of a shoe and thus retain the shoe in the desired rigid position during the polishing process. The lower edges of the sheet metal casing are bent upon themselves as at 9 to 70 provide a reinforcing means. The body of the brush 10 is provided with an aperture 11 at opposite points to receive a cap member 12 which is slidably mounted in the recess. The end wall 13 of the cap member 12 is provided with a concentric opening to receive the nail 14 or other suitable fastening means which is adapted to limit the movement of the cap against the tension of the spring 15. The cap members 12 are adapted 80 to engage the enlargements 16 formed on the sides of the casing to retain the brush in close proximity to the casing for an obvious purpose. A strip of metal 17 is secured to the back of the brush 10 providing means 85 for limiting the inward movement of the same.

When it is desired to use the polishing apparatus the brush is removed merely by a slight pressure on the member 17 which will 90 withdraw the brush member permitting access being had to the cloth shown and designated 18 in Fig. 2 and also the dauber 19 and the blackening box 6. By providing the end of the casing of the cabinet with an 95 annular portion to receive the shoe polishing box 6 any rattling or unnecessary noise thereof is avoided.

Having thus fully described my invention, what I claim as new, and desire to secure 100 by Letters Patent, is:

1. In a device of the character described the combination with a substantially oblong casing having the bottom wall thereof removed, of a brush member including a body 105 portion, the body portion having a recessed portion provided in the sides thereof, coiled springs mounted in said recessed portions, a cap member adapted to inclose the coiled springs, means extending through the cap 110

members into engagement with the body of the brush to limit the movement of the cap members, and enlargements formed on the casing adapted to receive the cap members for a purpose specified.

2. In a device of the character described the combination with a brush, of a casing, the bottom of the casing being open, the body of the brush forming a closure for said opening, enlargements formed on said casing, slidable plungers mounted on the body of the brush adapted to engage the enlargement to retain the brush within the casing, and a sheet metal member mounted on the

brush adapted to limit the inward movement thereof for a purpose specified.

3. In a shoe polishing cabinet, the combination with a brush, of a casing having the bottom thereof open, the body of the brush having recesses formed therein, plungers 20 slidably mounted in said recesses, and means associated with the casing to receive the plungers and thus retain the body of the brush within the open bottom.

In testimony whereof, I affix my signature 25 hereto.

REID J. McCREDIE.
